US00D991883S

(12) **United States Design Patent** (10) **Patent No.:** **US D991,883 S**
(45) **Date of Patent:** **** Jul. 11, 2023**

(54) **ELECTRIC VEHICLE CHARGING DEVICE**

(71) Applicant: **Zoox, Inc.**, Foster City, CA (US)

(72) Inventors: **Richard Luke Osellame**, Redwood City, CA (US); **Bryan Emrys Booth**, San Francisco, CA (US); **Moritz Boecker**, Millbrae, CA (US); **Timothy David Kentley-Klay**, Stanford, CA (US)

(73) Assignee: **Zoox, Inc.**, Foster City, CA (US)

(**) Term: **15 Years**

(21) Appl. No.: **29/865,664**

(22) Filed: **Aug. 5, 2022**

(57) **CLAIM**

The ornamental design for an electric vehicle charging device, as shown and described.

DESCRIPTION

FIG. 1 is a top perspective view of an electric vehicle charging device;

FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the electric vehicle charging device that form no part of the claimed design. The dot-dashed broken lines represent boundaries of the claimed device and form no part of the claimed design.

1 Claim, 8 Drawing Sheets
